JAMES S. STREETER, OF PROVIDENCE, RHODE ISLAND, ASSIGNOR TO HIMSELF AND CITY MACHINE COMPANY.

Letters Patent No. 80,783, dated August 4, 1868.

IMPROVEMENT IN FLY-FRAME FLIERS.

The Schedule referred to in these Letters Patent and making part of the same.

TO ALL WHOM IT MAY CONCERN:

Be it known that I, JAMES S. STREETER, of Providence, in the county of Providence, and State of Rhode Island, have invented an Improvement in the Method of Constructing Fly-Frame Flier; and I do hereby declare that the following is a full, clear, and exact description thereof, which will enable others skilled in the art to make and use the same, reference being had to the accompanying drawings, forming part of this specification.

This invention relates to a new and improved method of constructing fliers for twisting of yarn, whereby the same are more economically made.

It consists in making the same of malleable or annealed cast iron, and casting the legs upon a core, whereby the tube or tubes of a fly-frame flier may be formed up without drilling or reaming, and the top or back ear rolled or wound over.

In the accompanying plate of drawings—

Figure 1 represents a perspective view of the casting of which the flier is made.

Figure 2 is a front view of a flier finished.

Figure 3 is a side view of same.

Similar letters of reference indicate corresponding parts.

A. is the upper or back ear; G is a semicircular groove in the casting; α is a slot opening into said groove, as it appears after closing together of the two sides of groove G and the folding down of ear A, so that the said two sides do not quite touch each other.

The casting represented in fig. 1 is made of malleable or annealed cast iron, having the groove G in one leg of the same, and having upon its upper part the top or back ear, A, as shown in the drawing, fig. 1.

The groove is then folded or closed up, so as to form a tube, as shown in the drawing, fig. 2 and fig. 3, and the ear A is also rolled or folded inward, so as to take the form shown in fig. 2, so that the two edges of the same are brought nearly together, so as to form a tube having a slot through its entire length; and the ear A is bent or rolled down, so as to form a continuation of said tube and said slot, as shown in the drawings, figs. 2 and 3.

The advantages of constructing fliers as above described are, that they are more cheaply made, and more effectually prevent the roving from flying out when the flier is in motion.

I claim as new, and desire to secure by Letters Patent—

Constructing fly-frame fliers of malleable or annealed cast iron, with one or both legs cast with a groove upon a core or its equivalent, and with an ear, the flanges of said legs and the ear being rolled down, to form the grooved tube α , as herein shown and described.

JAMES S. STREETER.
